UNITED STATES PATENT OFFICE.

ALBERT E. VANDERCOOK, OF ALAMEDA, CALIFORNIA, ASSIGNOR TO CALIFORNIA MACVAN COMPANY, A CORPORATION OF CALIFORNIA.

AMALGAMATOR.

1,192,478.

Specification of Letters Patent. Patented July 25, 1916.

Application filed June 16, 1914. Serial No. 845,387.

To all whom it may concern:

Be it known that I, ALBERT E. VANDERCOOK, a citizen of the United States, and a resident of Alameda, county of Alameda, 5 and State of California, have invented certain new and useful Improvements in Amalgamators, of which the following is a specification.

The invention relates to amalgamators 10 for recovering gold and other valuable metals from the ores or sands containing the same.

One of the objects of the invention is to provide an amalgamator in which the ore 15 and metallic particles are positively brought into contact with the amalgamating surface.

Another object of the invention is to provide an amalgamator in which a high percentage 20 of the metallic particles is rapidly recovered.

Another object of the invention is to provide an amalgamator in which the ore particles are repeatedly brought into contact 25 with the amalgamating surface.

The invention possesses other advantageous features, some of which, with the foregoing, will be set forth at length in the following description, where I shall outline 30 in full that form of the invention which I have selected for illustration in the drawings accompanying and forming part of the present specification. In the drawings, I have shown only one specific form of my 35 generic invention, but it is to be understood that I do not limit myself to such form, because my invention may be embodied in a multiplicity of forms, each being a species of my said invention. It is also understood 40 that by the claims succeeding the description of my invention I desire to cover the invention in whatever form it may be embodied.

Referring to said drawings: Figure 1 is 45 a vertical section through one form of the amalgamator of my invention. Fig. 2 is a plan view of the amalgamator shown in Fig. 1.

The amalgamator of my invention consists of a vessel or tank 2, in the bottom of which is arranged a mercury coated amalgamating plate 3. Arranged within the tank above the plate 3 is an agitator, comprising a hollow rotatable hub 4 to which are attached 50 the hollow arms 5. Each arm is pro-

vided with a plurality of downwardly inclined nozzles 6 which are preferably flattened at their discharge ends, which discharge ends occur in close relation to the amalgamating plate. The hub 4 is preferably mounted upon the stationary depending conductor 7 by means of a liquid sealed anti-friction bearing, so that the agitator 60 may rotate freely with respect to the conductor 7. Liquid is forced downward 65 through the depending conductor 7, passes outward through the arms 5 and discharges from the nozzles 6 against the amalgamating plate 3, the reaction of the discharging jets of liquid serving to cause rotation of 70 the agitator. While I have termed the rotating structure an agitator and while its operation does produce an agitation of the liquid mass in the tank, the structure also 75 serves as a distributor and as a means for directing the ore and metallic particles into contact with the amalgamating plate.

The liquid carrying the finely ground ore and metallic particles is fed into the tank through the conductor 8 which preferably 80 is in communication at its other end with the ore classifier or thickener. The discharge end of conductor 8 occurs below the normal level of the liquid in the tank and is in juxtaposition with the intake end of the 85 suction pipe 9 of the pump 12, which operates to draw liquid from the tank and force it back into the tank through the conductor 7 and the agitator. By placing the discharge end of the feed pipe 8 in close relation 90 to the intake end of the suction pipe 9, the liquid being fed into the tank enters the pump suction and is forced through the nozzles into contact with the amalgamating plate. The ends of the pipes 8 and 9 are 95 preferably joined by a tee 13, the third opening of which is open and in communication with the liquid in the tank. By this arrangement the incoming liquid or slimes is forced into intimate contact with the 100 amalgamating plate and sufficient liquid is supplied to the pump, without producing a suction in the feed pipe, and the slimes in the tank are brought into recurrent contact with the amalgamating plate, thereby insuring a high extraction. This arrangement also prevents the pump from sucking air, which air has a deleterious effect when the amalgamation is being carried on in the presence of cyanid. 105

The tank is provided with an overflow pipe 14 which carries the slimes to a thickener or filter or to some other location. Arranged adjacent the bottom of the tank is 5 a valve controlled discharge pipe 15 which is opened to allow the contents of the tank to discharge when it is desirable to clean up. By suspending the agitator from above, the 10 surface of the plate is unbroken and by hoisting the agitator out of the tank, the plate may be quickly and thoroughly cleaned.

I claim:

1. In an amalgamator, a tank, a mercury covered plate arranged in said tank, a hollow armed rotatable structure arranged above said plate, nozzles on said structure directed toward said plate, a pump arranged externally of said tank and arranged to force liquid through said structure and nozzles, a suction pipe for said pump opening into the tank below the normal level of the liquid therein and a feed pipe extending into said tank and terminating below the normal level of the liquid therein and in close relation to the end of the suction pipe, whereby material discharging from the feed pipe is drawn directly into the suction pipe.

2. In an amalgamator, a tank, a mercury covered plate arranged in said tank, a hollow rotatable hub arranged above said plate, hollow arms extending from said hub and provided with apertures directed toward said plate, a pump arranged externally of said tank, connections between the discharge side of said pump and said hub, a suction pipe for said pump opening into the tank below the normal level of the liquid therein and a feed pipe connected to the suction pipe within the tank and below the normal level 40 of the liquid therein.

3. In an amalgamator, a tank, an amalgamating plate in said tank, a rotatable structure arranged to be rotated by the passage of liquid therethrough arranged adjacent said plate, a pump for withdrawing liquid from said tank and discharging it through said structure, and a feed pipe terminating within the tank and adjacent the intake end of said suction pipe.

4. In an amalgamator, a tank, an amalgamating plate arranged in said tank, a rotatable structure arranged to be rotated by the passage of liquid therethrough arranged above said plate, a pump connected at its discharge side to said structure, and a feed pipe passing through said tank and connecting with the suction side of the pump, provided with an aperture connecting the interior of said pipe with the liquid in the tank.

5. In an amalgamator, a tank adapted to contain slimes, an amalgamating plate in said tank, a stationary conductor depending into said tank, a rotatable structure adapted to be rotated by the passage of slimes therethrough mounted on said conductor and in close relation to said plate, a pump for withdrawing the slimes from said tank and discharging them through said structure, a pump suction pipe opening into the tank below the normal level of the slimes therein, and a slimes feed pipe extending into said tank and connected to the suction pipe below the normal level of the slimes in the tank.

In testimony whereof I have hereunto set my hand at San Francisco, California, this 10th day of June, 1914.

ALBERT E. VANDERCOOK.
